UNITED STATES PATENT OFFICE.

EDWARD L. FUCHS AND ANTHONY L. FUCHS, OF ST. LOUIS, MISSOURI.

GARMENT PROTECTOR FOR AUTO SEATS.

1,415,626.

Specification of Letters Patent.

Patented May 9, 1922.

Application filed June 11, 1921. Serial No. 476,842.

To all whom it may concern:

Be it known that we, EDWARD L. FUCHS and ANTHONY L. FUCHS, citizens of the United States, and residents of the city of 5 St. Louis and State of Missouri, have invented certain new and useful Improvements in Garment Protectors for Auto Seats, of which the following is a specification, containing a full, clear, and exact 10 description, reference being had to the accompanying drawings, forming a part hereof.

Our invention relates to a new and useful improvement in garment protectors for auto 15 seats, and has for its primary object the construction of a reversible seat back and a cover which not only protects the seat, but the garment of the occupant from becoming soiled.

20 In the drawings,

Fig. 1 is a plan view of our improvement.

Fig. 2 is a central section of the same in the position which it assumes when in use.

Fig. 3 is an enlarged sectional view taken 25 on the line 3—3 of Fig. 1, and Fig. 4 is an enlarged sectional view, showing the method of binding the rough or cut edges of the matting.

Referring to the drawings, 4 indicates the 30 cover for the back of a seat and 5 the cover for the seat and 6 the cover for the front end of the seat. These sections or portions are preferably made of straw or grass matting and in the construction of our improvement 35 we first apply the binding 7 to the lower edge of the back 4 and then apply the binding 8 to the rear edge of the seat 5. We then apply a strip of fabric 9 to the upper front edge of the seat 5 and the upper edge 40 of the portion 6 and we then apply a strip of fabric 10 on the underneath surface of the front edge of the seat 5 and on the back surface of the portion 6. After the above mentioned operations, we then take a continuous 45 piece of binding tape 11 and sew it along the top and sides of the back 4 and seat 5 and along the ends and lower edge of the portion 6. This continuous strip of binding tape 11 secures the portions 4, 5, 50 and 6 in assembled form and forms a hinged connection between the back 4 and seat 5 and reinforces the connection between the seat 5 and the portion 6. The pieces of fabric and the binding tape 11 are secured to 55 the back, seat and front portion 6 by means of stitching. Secured to the rear edge of

the seat 5 is a tape 13. These tapes are adapted to go around the seat and be tied for holding the cover in position on the seat.

It will be observed that the continuous 60 piece of binding tape 11 is stitched to the ends of the strips of fabric 9 and 10.

It will further be observed that the back 4 and seat 5 are secured together only at their ends so that the back 4 may conform to 65 the back of the occupant without putting any strain appreciably on the hinged connection between the back and the seat.

It is furthermore obvious that this construction will permit the back 4 to conform 70 to different shapes of the backs of seats.

It will further be observed that the rear edge of the seat portion 5 and the lower edge of the back portion 4 are spaced apart. Our protector is also reversible and when it 75 is desired to reverse the same, the strips 12 are inserted through the space between the sections 4 and 5 and then tied to the strips 13 around the seat.

In Fig. 4 we have illustrated the method 80 of binding the rough or cut edges of the matting, wherein we first fold over the edge of the matting and then apply the binding so as to prevent raveling or pulling apart, it being noted that the binding is stitched 85 through the folded edge of the matting. This is necessitated for the reason that the matting comes wider than is required for a seat cover and in trimming off the selvage to get the proper width and if the edge is not 90 turned over as illustrated in Fig. 4, the binding will pull out and carry with it a part of the matting and thus in a short time destroy the utility of our device.

Having fully described our invention, 95 what we claim is:

1. A reversible and flexible garment protector for auto seats composed of a section for the back, a section for the seat, and a section for the front edge of the seat, the 100 seat section and back section being spaced apart almost throughout their widths, a continuous piece of binding tape stitched at the outer margins of said section for holding the same in assembled form, the lower edge 105 of the back section and the rear edge of the seat section being unattached except at the side margins, so that the seat back section may conform with the shape of the seat back.

2. A reversible and flexible garment protector for auto seats comprising a section

for the back, a section for the seat, and a section for the front edge of the seat formed of grass or straw matting, a continuous strip of binding tape stitched to the outer 5 margins of said sections for holding the same together, the lower edge of the back section and the rear edge of the seat section being spaced apart and detached, except at their extreme outer ends, so that the seat 10 back section may conform with the curvature of the back of the seat on which it is used, the front edge of the seat section and the upper edge of the section for the front edge of the seat being connected together by 15 strips of fabric, said strips of fabric affording hinged connection between said sections and a protector covering for the upper front edge of the seat, and tapes secured to the rear edge of the seat section and the 20 lower edge of the section for the front edge

of the seat for removably securing the protector to the seat.

3. A reversible and flexible garment protector for seats, comprising a seat back section and a seat section formed of straw matting, adapted to be folded against each other, the adjacent edges of said sections being spaced apart and unattached, a flexible binding strip secured to three sides of each of said sections for flexibly connecting the same together at their sides only, so that the intermediate portion of the adjacent edge of each section may be conformed to either the seat or back without putting undue strain on the sections, thereby eliminating the danger of tearing.

In testimony whereof, we have signed our names to this specification.

EDWARD L. FUCHS.
ANTHONY L. FUCHS.
